UNITED STATES PATENT OFFICE

2,110,063

METAL MOLD FOR CASTING INGOTS

Septimus H. Griffiths, Canton, Ohio

Application November 9, 1936, Serial No. 109,988

3 Claims. (Cl. 22—139)

This invention pertains to an improved and novel metal mold for casting ingots and self-stripping the ingot therefrom, said mold being so designed as to constitute two sections, an upper major section and a lower minor section, said sections being horizontally separated, each section being formed with integral means at their meeting ends that jointly and simultaneously coact with each other to cause the upper section to be automatically guided and truly centered upon the upper face of the lower section, and to maintain the meeting face of the sections into true alignment between the shouldered portions thereof at the point of juncture and to form a tight joint at the said point.

The main object of the invention is to provide an improved simple, novel, economical, practical and thoroughly efficient self-stripping mold serving to produce a "large end up" ingot.

Another object of the invention is to so form and construct this two section mold that the inner wall thereof will be inclined gradually from its top to its bottom portion in true alignment and of such dimensions as to produce an ingot having a smooth exterior surface that will effectively prevent the formation of a fin or fissure around its outer surface at the point of juncture of the two sections.

Another object of the invention is to so construct the two sections of the mold that the lower section can be fixedly secured to any suitable or desirable support to prevent its movement away from said support when it is desired to lift the upper section carrying the ingot away from said lower section, and to permit the self centering of the two sections when placing the sections together in readiness for the casting operation.

Further objects of the invention are to so construct my improved sectional mold that it will dispense with the use of plugs of all kinds and types that have been heretofore employed for closing the open bottoms of the big end up mold and for pushing out the ingot from the mold; to dispense with inverted stripping of the mold; to eliminate the employment of costly plungers and other equipment heretofore employed for forcing the ingot out of the mold by the use of plugs to eliminate the use of all means heretofore utilized for fixedly securing the mold sections together at their point of juncture; to form a self-stripping mold, thereby saving time, labor, fuel and expense; to materially increase the quality and value of the ingot product.

The foregoing and such other objects as may appear from the ensuing description are accom-

plished by the combination, location, arrangement and construction of the several parts hereinafter more fully described, illustrated in the accompanying drawings, and particularly pointed out in the claims appended hereto, it being understood that slight changes in the precise shape, proportions, and minor details of the construction may be resorted to without departing from the spirit or sacrificing any of the advantages of the invention.

In the accompanying drawings forming a part of this specification, showing the type of mold involved for self-stripping the cast ingot therefrom, it will be seen that:

Figure 1 is a side elevation of the type of sectional mold embodied in my invention, showing means broken away and attached to a portion of the upper section for lifting it away from the lower section.

Figure 2 is a side elevation of the mold, showing means attached to the lower section and to the mold support for fixedly securing the lower section to said support.

Figure 3 is a sectional elevation of the mold shown in Fig. 1 with the lifting means removed.

Figure 4 is an enlarged sectional view taken in the plane shown by dotted lines 4—4, Fig. 2.

Figure 5 is a side elevation of the large upper section of the mold, showing said section and its lifting means partly in section and partly in full lines with the projected concaved end of the ingot carried by the section seated upon its support.

Figure 6 is a side elevation similar to that shown in Fig. 5, showing the lower end of the upper mold section and the ingot seated upon the support with the upper end of the ingot projected above the upper end of the mold section, and in full lines the means clamped to the ingot for lifting it away from said section.

Figure 7 is an inverted plan of the upper section of the mold, and

Figure 8 is a plan of the lower section of the mold.

In the embodiment of my invention it will be seen that the numeral 2 designates the upper major section of the mold formed with integral laterally extended lugs 3 at its upper end portion for the reception of suitable detachable lifting means 4 for lifting and moving the section away from contact with the lower minor section 5 of the mold, the lower end of said major section, at two opposite sides thereof, being provided with a continuous depending extension 6 in alignment with its outer wall and formed at its

lowermost end with a horizontal seating face 7 and an upwardly and inwardly beveled portion 8 terminating with a vertical wall or shoulder 9 which terminates at the horizontally extending 5 meeting face 10 of the section forming the point of juncture with the upper face of the minor section, as is clearly shown in Fig. 3 of the drawings, while the lower minor section 5 is formed at its upper end with similar but upwardly extended integral formations 11 at opposite sides thereof in alinement with its outer wall and reversely beveled, as shown in Fig. 4, so that when it is desired to join the sections together it is simply necessary to lower the upper section 2 10 until its lower extended beveled end portions contact with the upper and outer end portions of the minor section when by further lowering said upper section will be automatically guided to the point of juncture of the two sections into 15 contact with each other, with the extensions 6 of the major section overlapping the outer wall of the upper end of the minor section at opposite sides thereof and the upward extensions 11 of the minor section overlapping the lower outer walls 20 of the upper section at its opposite sides and above its meeting face as shown by the dotted lines in Figs. 1 and 2, while the vertical shouldered or wall portions of the extensions 6 and 11 simultaneously serve to embrace and contact with 25 the outer wall of the upper portion of the lower section and the outer wall of the upper section, respectively, thereby maintaining the sections in proper relation to each other, thus causing the meeting faces of the sections which are preferably so machined as to form a true, accurate and tight juncture of the said meeting faces when joined together for the ingot casting operation.

Both of the mold sections are preferably formed of cast iron, and when united at the point of juncture the inner wall is inclined inwardly from 40 the top to the bottom thereof, terminating with a concaved solid bottom, said formation being provided for the production of "large end up" ingots and for eliminating and dispensing with 45 the use of all types of plugs and other expensive equipments heretofore employed in connection with molds for stripping the cast ingots 12 from their molds.

By the construction of my improved formation 50 of "large end up" horizontally separated sectional mold the molten metal assures progressive solidification from the bottom to the top of the ingot; serves to prevent the formation of piping and blow holes on or near the surface which is 55 essential to soundness and homogeneity; the production of a higher grade and quality of ingot possessing a smooth exterior surface, and adds to the intrinsic value and quality of the rolled product produced from the ingot.

It will also be readily perceived that by this 60 specially designed type of mold all means heretofore employed for securing and locking the sections together are entirely dispensed with, hence neither time nor labor is required for releasing 65 and unlocking such fastening means, since the larger upper section 2 is simply lowered and is automatically guided by the coaction of all of the aforesaid beveled extensions until the meeting faces truly and smoothly contact with and are 70 held in their properly alined position by the vertically disposed shouldered or wall portions formed entirely around the mold at the point of juncture of the mold sections.

It will be seen that the lower minor section of 75 the mold is provided with an excess of metal at

the bottom thereof for more rapidly cooling and solidifying the bottom portion of the ingot, and is formed with a concaved inner lowermost wall for forming an ingot having a convexed lowermost end, while its outer wall at the bottom portion thereof is provided with an integral projected lug 13 oppositely disposed for the reception of one end portion of an elongated metal link 14, said link being adapted to be swung over a fixed lateral extension 15, forming a part of the 10 mold support 16 for the reception of the other end portion of the link, said link and extensions serving to maintain the said minor section of the mold in fixed position with relation to the mold support, while the upper major section of the 15 mold carrying the entire ingot is lifted and moved away from the lower minor section to another position and seated upon said mold support 16.

While my special type of mold sections is shown 20 as being substantially square in contour with rounded outside and inside corners in cross-section, it will be obvious that said sections may be of rectangular, oval, oblong, circular, or other desirable formation required to produce the shape 25 of ingot that may better serve the purpose for which it is intended.

It will be readily evident that this particular construction of mold for casting ingots or slabs is adapted for use in connection with all kinds 30 of molten metals, especially with relation to what is commonly known in the art as "rimming or effervescent steel", and that the several parts of the mold may be formed of any suitable or desirable dimensions best adapted for the purpose 35 for which it may be utilized.

It is well known in the steel manufacturing art that ingot plants and foundries are equipped with various movable types of lifting and conveying means, which may be readily engaged and disengaged from the molds and ingots for transferring them from one place to another when desired. Hence, since the special construction of 40 such equipment forms no part of this invention, it has not been deemed necessary to further illustrate and describe such equipment.

What I claim and desire to secure by Letters Patent is:

1. A metal mold for casting self-stripping ingots, comprising two sections, an upper major section and a minor lower section separated horizontally from each other, the major section having a downwardly extended portion at its lower end below its meeting face at opposite sides thereof in alinement with its outer wall and overlapping the outer wall of the minor section at its upper end portion entirely across said upper portion at opposite sides thereof, the minor section having an upwardly extended portion at the upper end thereof in alinement with its outer wall 50 overlapping the outer wall of the upper section at its lower end at opposite sides thereof above its meeting face and entirely across its outer face between its extended portions, said extended portions forming a continuous inner wall entirely 55 around the meeting faces of both sections of the mold.

2. A metal mold for casting self-stripping ingots, comprising two sections, a major section and a minor section horizontally separated from each other, the major section being formed with depending portions at its lowermost end in alinement with its outer wall extending entirely across two opposite sides thereof and overlapping the outer upper end wall of the minor section entire- 75

ly across two opposite sides thereof below the meeting faces of the mold, the minor section having upwardly extended portions at its upper end in alinement with its outer wall and overlapping the outer wall of the major section at its lower end at opposite sides entirely across its opposite sides between the depending portions thereof above the meeting faces of the mold, the minor section having a solid bottom with a concaved inner wall, the inner surface of the said depending portions and the upwardly extended portions being reversely beveled and formed with a vertically disposed shouldered portion or wall adapted to engage with the outer walls of the said sections, all of the extended portions simultaneously co-acting and serving to form a continuous vertically disposed inner wall around the meeting faces of the mold and to automatically guide, center and maintain the meeting face of the sections into true and accurate alinement at the point of juncture and to form a tight joint at said point.

3. A metal mold for casting self-stripping ingots, comprising two sections, an upper major section and a minor lower section separated horizontally from each other, the major section having a downwardly extended portion at its lower

end below its meeting face at opposite sides thereof in alinement with its outer wall and overlapping the outer wall of the minor section at its upper end portion entirely across said upper portion at opposite sides thereof below the meeting faces of the mold, the minor section having an upwardly extended portion at the upper end thereof in alinement with its outer wall overlapping the outer wall of the upper section at its lower end at opposite sides thereof above its meeting face and entirely across its outer face between its extended portions above the meeting faces of the mold, said minor section having a solid bottom with a concaved inner wall, a support for the mold disposed below said sections, means for fixedly securing the minor section to said support, consisting of two projected formations oppositely disposed near the bottom of said minor section for the reception of one end of an elongated link, and a fixed member disposed at opposite sides of the support for the reception of the other end of the link, so that the link may be readily swung over the said fixed members, thereby fixedly securing the minor section to the support.

SEPTIMUS H. GRIFFITHS.
